(57) **CLAIM**

The ornamental design for a three-light source desk lamp, as shown and described.

DESCRIPTION

FIG. 1 is a front, top perspective view of a three-light source desk lamp design showing my new design.

FIG. 2 is a front view of a three-light source desk lamp.

FIG. 3 is a rear view of a three-light source desk lamp.

FIG. 4 is a left side view of a three-light source desk lamp.

FIG. 5 is a right side view of a three-light source desk lamp.

FIG. 6 is a top view of a three-light source desk lamp.

FIG. 7 is a bottom view of a three-light source desk lamp.

FIG. 8 is a bottom perspective view of a three-light source desk lamp.

FIG. 9 is another perspective view thereof, showing the three-light source desk lamp in an alternate position.

FIG. 10 is an enlarged view of a three-light source desk lamp taken from the circle part in FIG. 2; and,

FIG. 11 is an enlarged view of a three-light source desk lamp taken from the circle part in FIG. 2. The broken lines framing portions of the claimed design are included for the purpose of illustrating enlargements, and form no part of the claimed design.

1 Claim, 11 Drawing Sheets
